UNITED STATES PATENT OFFICE.

STEVINE TOMCSAMYI, OF WILLOCK, PENNSYLVANIA.

FOLDABLE SUPPORT.

1,242,274.

Specification of Letters Patent.

Patented Oct. 9, 1917.

Application filed July 31, 1914. Serial No. 854,417.

To all whom it may concern:

Be it known that I, STEVINE TOMCSAMYI, a subject of the King of Hungary, residing at Willock, in the county of Allegheny and 5 State of Pennsylvania, have invented certain new and useful Improvements in Foldable Supports, of which the following is a specification, reference being had therein to the accompanying drawing.

10 This invention relates to a foldable support, and has for its object to provide a device of such class, in a manner as herein-after set forth, capable of supporting articles of wearing apparel and further capable 15 of being folded in a compact manner when not in use.

Further objects of the invention are to provide a foldable support for the purpose set forth which is simple in its construction 20 and arrangement, strong, durable, efficient and convenient in its use, readily set up and knocked down, and inexpensive.

With the foregoing and other objects in view the invention consists of the novel construction, combination and arrangement of parts as hereinafter more specifically described and illustrated in the accompanying drawings wherein is shown an embodiment of the invention, but it is to be understood 30 that changes, variations and modifications can be resorted to which come within the scope of the claim hereunto appended.

The drawing illustrates in perspective a foldable support in accordance with this invention, the support being extended, as well as broken away.

Referring to the drawing the support is formed of two sections and as each section is similar in construction, but one will be 40 described as the description of one applies to the other.

Each of said sections includes a vertical disposed upright 1, having connected to its outer face, near the top thereof, an extension 2 which projects above the top of the upright 1, the outer face of the extension 2, intermediate its upper and lower ends, has connected thereto a plurality of hooks 3, and said extension has secured to each side 45 thereof a keeper 4.

Secured to the inner and outer faces of the extension 2, near the top thereof, is a transverse bar 5, of a length to project beyond each side edge of the extension 2. The 55 bars 5 are arranged in parallelism and piv-

otally connected between the projecting portions of the bars 5, at each side edge of the extension 2, is a supporting arm 6. The pivot for each of said arms 6 is indicated at 7. Each of said arms 6 has hinged thereto a brace 8, which is adapted to have its lower end engaged in a keeper 4 for bracing the arm 6 when the latter is extended. The arms 6 are capable of folding against the side edges of the extension 2, when the 60 braces 8 are moved from the keeper 4.

The outer face of the extension 2 has a plurality of eyes projecting outwardly therefrom, said eyes are indicated at 9, and are capable of having articles attached thereto, 70 the lower end of the extension 2 carries a loop 10 for the purpose of supporting an article of clothing.

Secured to the outer and inner faces of the upright 1, near the lower end of the extension 2, is a transverse bar 11, having its ends projecting beyond each of the side edges of the upright 1. The bars 11 are arranged in parallelism and pivotally connected between the projecting portions of the bars 11, at each side of the upright 1, is a supporting arm 12. The pivot of the arms 12 are indicated at 13 and each of the said arms 12, when extended, is braced through the medium of an inclined member 85 14. The members 14 are hinged to the lower faces of the arms 12 and are adapted to have their lower ends engaged in keepers 15, secured to the side edges of the upright 1, whereby the arms 12 will be supported in 90 an extended position. The arms 12 are capable of being folded against the side edges of the upright 1 when the members 14 are moved from engagement with the keepers 15.

The inner face of the upright 1 has attached thereto hooks 16 for supporting articles of wearing apparel and the other face has projecting therefrom an eye 17 on which an article can be attached whereby the article is supported.

Each section of the support further includes a base formed of a detachable section 17, and a section 18, which is hinged as at 19 to the lower end of the upright 1. The section 17 of the base is coupled to the section 18 through the medium of hooks 20, carried by one of the base sections and engaging in eyes 21 carried by the other section of the base.

Each of the sections has attached to its 110

upper face a keeper 22, for the lower end of a brace member 23, which is attached as at 24, to a side edge of the upright 1.

Loosely connected to the side edges of the 5 upright 1, as at 24', are brace members 25, which have pointed ends 26 to engage the surface upon which the support is mounted whereby the upright 1 is braced.

The upright 1 of one section of the 10 support is connected to the upright 1 of the other section of the support, by a detachable and likewise adjustable coupling bar 27.

What I claim is: —

A support comprising a pair of foldable 15 sections connected together and each consisting of a base, an upright mounted thereon, an extension secured to each upright in position to project thereabove, a pair of lateral arms pivotally supported on each ex-

tension projecting in opposite directions, the 20 braces therefor detachably engaged with the side edges of the extension, additional lateral arms pivotally carried on the upright and projecting in opposite directions, braces for 25 said additional arms detachably engaged with the side edges of said uprights, an arm pivotally engaged with one side edge of the upright, a keeper on the base to receive the free end of said last mentioned brace in engagement therewith, whereby to 30 support the upright in vertical position on the base.

In testimony whereof I affix my signature in the presence of two witnesses.

STEVINE TOMCSAMYI.
